Term of patent 14 years

(Cl. D49—1)

FIG. 2

FIG. 1

Figure 1 is a front perspective view of a laundry machine cabinet or similar article showing my new design; and

Figure 2 is a cross sectional view taken through the top unit of the cabinet substantially along line 2—2 of Figure 1.

The essential features of the design as shown in the foregoing figures reside in the portions shown in full lines.

I claim as my invention:

The ornamental design for a laundry machine cabinet or similar article, as shown and described
